FIG. 13.

UNITED STATES PATENT OFFICE

GEORGE H. BENT, OF BATTLE CREEK, MICHIGAN

CARTON FEEDING MACHINE

Application filed June 28, 1927. Serial No. 202,134.

This invention relates to package making machines, and more particularly to machines for feeding carton blanks or the like to said machines.

6 One object of the invention is to provide mechanism that will move a blank or the like into position on a continuously moving form therefor.

Another object of the invention is to provide 10 mechanism that operates on the successive blanks of a stack, to open, recollapse, reopen, square out and transfer the blanks onto forms or holders for the same.

Another object of the invention is to provide 15 a blank separating and forwarding knife or the like that travels in an orbital or closed path to separate and forward blanks from a stack of the same.

Another object of the invention is to provide 20 a blank separating, opening and forwarding knife that carries the carton through rollers for recollapsing the same.

Another object of the invention is to provide 25 a mechanism that acts, during travel of the knife in its orbital path, to rotate the knife and open the carton.

Another object of the invention is to provide 30 a reciprocating carton receiver with devices movable thereon to square out a carton in the receiver.

Another object of the invention is to provide 35 a carton receiver with flap spreading devices thereon for opening the flaps of the carton prior to transfer of the same onto a form.

A further object of the invention is to provide 40 a carton receiver with a stripping device that transfers the carton from the receiver onto the carton form.

45 Other objects of the invention will appear as this description thereof proceeds.

The invention as herein illustrated and described is, or may be, associated with any suitable package making machine such as disclosed, for example, in Patent No. 1,096,918, granted to H. L. Johnson, May 19, 1914. It is to be expressly understood, however, that the invention is not limited in use to the type of package making machine referred to and 50 that the invention may be embodied in single

or in tandem form with package making machines that operate at higher speeds and have greater capacity of production than the package making machine disclosed in said patent and described and illustrated herein. 55

In order to more clearly understand this invention reference may be had to the accompanying drawings which illustrate one embodiment of the inventive idea and wherein

Fig. 1 is a side elevation of a package making machine, showing blank feeding mechanism of the present invention associated therewith;

Fig. 2 is a side elevation of the blank feeding mechanism, looking from the left of Fig. 1;

Fig. 2^a is a detail perspective view of the front end of the blank feeding mechanism, with parts omitted to more clearly show the blank recollapsing rollers; 70

Fig. 3 is an enlarged top plan view partly in section, of the blank feeder and associated package making machine, with parts of both omitted for purposes of clearer illustration;

Fig. 4 is a pulled out perspective view, 75 showing a carton pusher, and carton blanks at successive positions occupied thereby during travel of the same from the feeder mechanism to the package making machine;

Fig. 5 is an enlarged detail perspective view showing the carton blank opening and forwarding knife, together with parts of the mechanism for operating the same;

Fig. 6 is a detail perspective view of the vertical pivotal connection for the knife with the reciprocating support therefor;

Fig. 7 is a detail perspective view of flap spreading and carton stripping devices;

Fig. 8 is a diagrammatic view showing reciprocating squaring out mechanism with a blank therein ready to be transferred onto the moving carton form or block;

Fig. 9 is a side elevation, partly in section, of devices for spreading the end flaps of the carton as the latter is being transferred from the squaring out mechanism onto the carton form or block; 95

Fig. 10 is a side elevation of a carton stripper that ejects the carton from the squaring out mechanism onto the form or block; 100

Fig. 11 is a detail perspective view of flap spreading fingers and a plunger for operating the same;

Fig. 11^a is a transverse sectional view on the line 11^a, 11^a of Fig. 7;

Fig. 11^b is a longitudinal sectional view on the line 11^b, 11^b of Fig. 9;

Fig. 12 is an enlarged detail perspective view of the squaring out mechanism, showing the connections for operating said mechanism and the flap spreading and carton stripping devices carried thereby;

Fig. 13 is a detail perspective view of a carton form or block equipped with flap spreading fingers and means for operating the same;

Figs. 14 and 15 are longitudinal and transverse sectional views respectively, through the form or block shown in Fig. 13; and

Fig. 16 is a detail perspective view of a carton form or block equipped with pneumatic flap spreading means.

Referring to the drawings, wherein like reference characters designate like parts throughout the several views, the principal instrumentalities there shown are comprised by a package making machine, stack feeder, blank engaging knife and recollapsing rollers, carton blank pushing and registering means, carton squaring out mechanism, and flap spreading and carton stripping devices, which will be described in the order named.

Package making machine Figs. 1, 2 and 3

This machine is provided at each side thereof with upper and lower frames 5 and 6 respectively that are connected together by transverse tie members 7, 7 and 8, 8 and supported on legs 9, 9 bolted or otherwise suitably secured to the machine room foundation 10. The package making machine is driven from any suitable source of power, such as an electric motor 11, which is bolted or fastened in any desired manner to the machine foundation 10. The armature shaft 12 of this motor carries a pulley 13 around which passes a belt 14 that also passes around a pulley 15 fixed on a shaft 16 that is journaled in suitable bearings on the machine framework at the bottom thereof. The shaft 16 has fixed thereon a pulley 17 around which passes a belt 18 that also passes around a pulley 19 fixed on a shaft 20 journaled in suitable bearings on the machine frame work at the upper part thereof. Fixed on the shaft 20 is a pulley 21 around which passes a belt 22 that also passes around a pulley 23 keyed or otherwise rigidly secured on a shaft 24 journaled in suitable bearings on the framework at one end thereof.

The shaft 24 extends transversely of the machine between upper and lower raceways 25 and 26 respectively that are bolted or otherwise suitably secured to the tie members 7, 7 and project outwardly beyond the machine

from the end thereof opposite that carrying the shaft 24. Fixed on the shaft 24 are sprockets, one of which is indicated at 27 (Fig. 1). Passing around said sprockets are chains 28, 28 that also pass around sprockets 29, 29 fixed on a shaft 30 journaled in suitable bearings on the projecting ends of the raceways 25, 26 (Fig. 2). Fixed on the chains 28, 28 at suitable intervals along the same are plates 31, 31 to which are attached carton forms or blocks 33, 33 and carriers 32, 32 disposed in alternate relation along the conveyor comprised by the chains 28, 28 and moving continuously therewith during like motion imparted to said chains by the driving connections therefor with the motor 11 or other source of power. In the designed use of this machine, the carton forms or blocks 33, 33 serve to carry empty cartons past sealing devices such as disclosed in Patent No. 1,096,918, which devices seal the bottom flaps of the empty cartons. The carriers 32, 32 serve to carry filled cartons past said flap sealing devices to seal the top flaps of the packages.

Stack feeder, Figs. 1, 2, 2^a, 3 and 12

The stack feeder herein disclosed is mounted on a suitable support comprised by side frames 34 and 35 connected together by transverse tie members 36, 36 and provided with legs 37, 37 bolted or otherwise suitably secured to the machine foundation 10. The stack feeder may be driven from any suitable source of power, but as herein shown, is preferably driven from the package making machine by the following instrumentalities. Fixed on the shaft 30 is a sprocket 38 around which passes a chain 39 that also passes around a sprocket 40 fixed on one extremity of a cam shaft 41 extending longitudinally of the feeder framework. This shaft 41 is journaled in suitable bearings 42, 42 carried by a pair of the tie members 36, 36 that connect the side frames 34 and 35 of the feeder together. Fixed on the shaft 41 is a cam 43 that engages a roller 44 journaled on a fork 45 straddling the shaft 41 and carried on the lower end of a rod 46 that is moved upwardly by the cam during rotation thereof with the shaft 41. The upper end of the rod 46 is pivotally connected at 47 with an arm 48 which is loosely mounted on a shaft 49 and turns in a counterclockwise direction thereon on upward movement of the rod 46. The arm 48 carries a pawl 50 which, during said counterclockwise turning movement of the arm 48, rides idly over the teeth of a ratchet wheel 51 that is keyed or otherwise rigidly secured to the shaft 49 and with the latter is normally retained against movement in one direction by a pawl 51^a (Fig. 3). The pawl 51^a is pivoted on a rod 51^b adjustably retained, as by a set screw 51^c, in a bracket 51^d bolted or otherwise rigidly secured on the side frame 34 of the feeder.

Pivoted at 52 on the free end of the arm 48 is a rod 53 carrying one or more weights 54, 54 which, after each raising movement of the rod 46, tend to turn the arm 48 in a clockwise direction and engage the pawl 50 with one of the teeth of the ratchet wheel 51 to thereby partially rotate said wheel in the same direction. Fixed on the shaft 49 are sprocket wheels 55, 55 around which pass chains 56, 56 that also pass around sprocket wheels 57, 57 fixed on a shaft 58. Shafts 49 and 58 are journaled in suitable bearings on the tops of the frames 34 and 35 and the sprocket wheels carried by said shafts are preferably adjustable along the same to vary the distance between the chains 56, 56 as desired. The upper reaches of the chains 56, 56 are preferably supported on guides 56', 56' secured by brackets to the side frames 34 and 35. Said upper reaches of the chains 56, 56 support a stack of collapsed carton blanks 59 and forward the same to a platform 60 where the collapsed carton blanks are fed in succession off the front of the stack by a knife to be hereinafter described. In the forwarding movement of the stack of collapsed blanks on the chains 56, 56, said blanks are guided and retained against displacement from the chains, by guide rails 61, 61' that are adjustable toward and away from each other to accommodate carton blanks of various sizes.

For this purpose the guide rails 61, 61' are supported by brackets 62, 62 through suitable openings in the lower ends of which are threaded rods 63, 63 journaled in the bearings 64, 64 on the tops of the frame members 34 and 35. The brackets 62, 62 also support the guides 56', 56' for the chains 56, 56. Fixed on the ends of the rods 63, 63 are hand wheels 65, 65 which may be turned to move the guide rails 61, 61' toward or away from each other in accordance with the direction of rotation of said hand wheels. The chains 56, 56 preferably carry on the upper reaches thereof, a follower 66 which engages the rear of the stack of blanks and, during movement of said chains, presses the front of the stack against stop members 67, 67 that engage over the edges of the foremost blank of the stack. The stop members 67, 67 are yieldably mounted, as hereinafter described, to provide for removal of the blanks from the front of the stack.

When the stack is maintained with sufficient pressure against the stops 67, 67, movement of the chains 56, 56 is stopped and the arm 48 has only a slight turning movement downwardly so that the distance traveled by the pawl is less than the pitch of one of the teeth of the ratchet wheel 51. When a sufficient number of blanks have been removed from the front of the stack, however, the weights 54, 54 will impart a downward turning movement to the arm 48 that is sufficient

to engage the pawl 50 with one of the teeth of the ratchet wheel 51 and impart a partial rotation to the same, thus causing the upper reaches of the chains 56, 56, the weight 66, and the stack of blanks 59, to move forwardly until proper pressure of the stack against the stops 67, 67 is obtained. The stops 67, 67, as before stated, are yieldably mounted to provide for removal of the blanks in succession from the front of the stack. For this purpose, said stops are preferably secured at 68, 68, to collars 69, 69 that are fixed on shafts 70, 70, journaled in arms 71, 71 that project from side rails 61, 61' and are bolted or otherwise suitably fastened thereto. Fixed on the shafts 70, 70 are arms 73, 73 to the free ends of which are connected springs 74, 74 that are also connected at 75, 75 with the brackets 72, 72'. The springs 74, 74 maintain the inner ends of the stops 67, 67 in engagement with the front of the stack 59, but as the front blank of the stack is removed by the knife above referred to, the springs 74, 74, together with the stops 67, 67 yield so that the inner ends of said stops are moved outwardly beyond the edges of the collapsed blank through the displacement of the blank by said knife. As soon as a blank is removed from the front of the stack, the stops 67, 67 are swung inwardly by the springs 74, 74 and 75 engaged over the edges of the succeeding blank.

Blank engaging knife and recollapsing rollers, Figs. 1 to 6 inclusive

The foremost blanks of the stack 59 rest on the plate 60 as before stated, said plate being carried by an inverted U-shaped bracket 59' (Fig. 2^a) secured to the slide frames 34 and 35 of the machine. The collapsed blanks are fed in succession off the front of the stack by a knife 76 which in each cycle of its operation moves rearwardly so that the upper beveled end 77 of said knife is engaged with the rear side flap 78 of a collapsed blank 79 (Fig. 4). One 110 of the narrow end flaps 80, 80 of the blank 79 is cut shorter than the other, to facilitate engagement of the knife with the flap 78, and insertion of the knife within the collapsed blank 79. After the knife 76 is engaged with the flap 78, said knife is moved upwardly into the collapsed blank 79 and then forwardly with a rotating motion on its longitudinal axis to separate the blank from the front of the stack and disengage said blank from the 115 stops 67, 67. During forward travel of the blank 79 with the knife 76, the edges 81, 81 of the blank engage curved end portions 82 and 83 of the guide rails 61 and 61' respectively (Figs. 2^a and 3). The curved end portions 82 and 83 of said guide rails engage the edges 81, 81 of the blank 79 as it travels forward with the knife 76 and with the latter act to open the blank as indicated at the position A thereof in Fig. 4. As the blank 120

is opened out, the edge of the forwardly moving knife 76 is engaged in the corner of the blank at the fold line 84 thereof. Further forward movement of the blank with the knife and engagement of the blank with the curved portion 82 of the guide rail 61 swings the opened blank around to the position B. The edge of the blank at the fold line 84 thus becomes the leading edge and is drawn by the knife 76 through a pair of rollers 85, 85 as indicated at the position C of the blank. The rollers 85, 85 recollapse the blank 79 and tend to take the spring out of the same, by bending the rear and side panels of the blank in directions opposite to the directions in which said panels were bent when the blank was first collapsed.

The forwardly moving knife 76 while drawing the blank through the rollers 85, 85 travels between a straight guide rail 86 and a plate or support 87. The forward end of the plate 87 is supported on a bracket 87' (Fig. 3) secured to the side frames 34, 35, and the guide rail 86 is supported by brackets (not shown) secured to said plate. After the rear edge of the recollapsed blank has cleared the rollers 85, 85, said blank, due to the inherent spring thereof, reopens and swings about the knife to the position D. In this position of the blank it is engaged by a pusher 88 which, together with the knife 76, moves the reopened blank forwardly on the plate 87 in engagement with guide rail 86 and with a guide rail 89 carried by brackets (not shown) bolted or otherwise suitably secured on said plate. The guide rail 89 has a curved end portion 90 with which the reopened blank 79 is engaged at the position D thereof. It will thus appear that when the pusher 88 starts to move the reopened blank forwardly, said blank through its engagement with the straight guide rail 86 and the curved portion 90 of the guide rail 89 will be turned around the knife 76 to the position E where the blank is registered against stops 144, 144. When the blank reaches the position E, the knife is withdrawn from the blank and is thereafter turned into position for re-insertion into the next succeeding blank, the knife 76 then being moved rearwardly of the feeder into engagement with the next collapsed blank of the stack 59.

The above described movements of the knife 76 are preferably imparted thereto through the medium of the following instrumentalities. The raising and lowering movements of the knife are derived from a cam 91 fixed on the cam shaft 41 and provided with a groove 92 in which is engaged a roller 93 journaled on an arm 94 that extends transversely of the framework of the feeder (Fig. 2). The arm 94 is loosely mounted on a rock shaft 95 that is journaled in suitable bearings 96, 96 carried by the side of frame 35 at the bottom thereof. Pivots

connected with the arm 94 is one end of a connecting rod 97 the opposite end of which is pivotally connected with an arm 98 fixed on a shaft 99 that extends transversely of the feeder and is journaled in suitable bearings on the side frames 34 and 35 thereof (Fig. 5). Fixed on the shaft 99 is an arm 100 the free end of which is pivotally connected at 101 with the upper end of a link 102. The lower end of the link 102 is pivotally connected at 103 with a bar 104 which, through the above described connections, is reciprocated vertically in a guide block 105 formed integrally with a crosshead 106 that is reciprocated horizontally by means to be presently described. The guide block 105 is provided with a groove 107 that receives the vertically reciprocating rod 104, said rod being retained in the groove 107 by guide plates 108, 108 that engage over the rod 104 and are removably secured to the front face of the guide block 105, as by machine screws 109, 109.

The upper end of the rod 104 terminates in a stud 110 that forms a bearing for a knife holder 111. The knife holder 111 is rotatably mounted on the stud 110 and is retained against displacement therefrom by a pin 112 that extends outwardly from the stud 110 at right angles thereto and engages in an elongated slot 113 in the holder 111. The slot 113 coats with the pin 112 to retain the knife holder 111 on the stud 110 and at the same time provides for rotation of said holder and the knife during reciprocating movement thereof with the rod 104. Mounted in ears 114, 114 that project from the knife holder 111, is a horizontally extending pin 115 on which is journaled a sleeve 116 having secured thereto or formed integrally therewith an L-shaped bracket comprised by arms 117 and 118. The knife 76 is secured to the arm 117 of said bracket as by machine screws 119, 119 that pass through aligned openings in the lower end of the knife and in the arm 117 respectively.

The movement of the knife forwardly and rearwardly of the feeder is derived from a cam 120 that is fixed on the cam shaft 41 forwardly of the cam 91 thereon. This cam 120 is provided with a groove 121 in which is engaged a roller 122 that is rotatably mounted on an arm 123. The arm 123 is loosely mounted on the rock shaft 95 and is pivotally connected with the lower end of a rod 124 the upper end of which is pivotally connected with an arm 125 of a bell crank lever 126 that is loosely mounted on the shaft 99. The other arm 127 of the bell crank lever 126 is pivotally connected at 128 with one extremity of a link 129 the opposite extremity of which is pivotally connected at 130 with the cross head 106. The cross head 106, through the connections therefor with the cam 120, is reciprocated horizontally in a

groove 131 of a guide bracket 132, the cross-head 106 being retained in the groove 131 of the guide bracket 132 by plates 133, 133 that are secured to the guide 132, as by machine screws 134, 134. Projecting from the guide 132 and preferably formed integrally therewith are brackets 135, 135 that are bolted or otherwise suitably secured at 136, 136 to the feeder frame 35 as clearly shown in Fig. 1 of the drawings.

5 The knife 76, as before stated, is partially rotated during the forward movement thereof and this partial rotation of the knife is preferably obtained through the medium of the following instrumentalities. Projecting horizontally from the holder 111, and preferably formed integrally therewith, is an arm 137 on the free end of which is journaled a roller 138. After the knife 76 has been moved upwardly into the blank 79 and starts to travel forwardly, the roller 138 strikes a cam 139, thereby turning the arm 137 rearwardly and turning the knife 76 so that its edge is engaged with the fold line 84 of the blank at the inner side thereof. The cam 139, as clearly shown in Fig. 3 is of sufficient length to hold the arm 137 in its rearward position until the knife 76 and the pusher 88 have moved the reopened carton blank to the 25 position E thereof in Fig. 4 of the drawings.

30 At this point, the cam 93 and the connections therefor with the rod 104, move the latter and the knife downwardly so that the roller 138 is disengaged from the cam 139. 35 When the roller 138 is disengaged from the cam 139, a spring 140 having its ends connected with the stud 110 and the knife holder 111, rotates the knife holder, the arm 137 and the knife 76, in the opposite direction to that 40 in which said elements were rotated by the cam.

After the second rotation of the knife it is moved rearwardly by the crosshead 106 and the connections therefor with the cam 120. 45 Near the limit of its rearward movement, the knife engages the rear side flap 78 of the next carton on the front of the stack 59. In order to relieve the strain of engagement of the moving knife with the carton and to provide for variations in position of the front of the stack, a spring 141 is interposed between the bracket arm 118 and the top of the holder 111 so that when the knife 76 strikes the carton blank, said knife will yield slightly 50 with a turning movement about the pivot 115, thereby compressing the spring 141. When the knife has been moved upwardly into the carton and starts forwardly with the same, the tension on the spring 141 is relieved 55 and the knife turns slightly in the opposite direction about the pivot 115, this turning movement of the knife being limited and adjusted by a set-screw 142 having threaded engagement in an opening forward in a bracket 143 that overhangs the bracket arm

118 and is secured to or formed integrally with the knife holder 111. From the foregoing it will appear that the knife 76 travels continuously in an orbital path at points in which the knife is turned in opposite directions during reciprocating movement of the same. It will further appear, that in each cycle of operation of the knife in the closed orbit, the upward, forward, downward, rearward and turning movements thereof are 70 utilized to disengage a blank from the front of a stack 59, open and forward said blank, and recollapse and deliver the same in re-opened condition to other instrumentalities that act on the blank in a manner to be presently described.

Blank pushing and registering means, Figs. 1, 2, 3, 4

The blank pusher 88 above referred to, in 85 the position of the opened blank indicated at D in Fig. 4, engages the rear of the blank and with the knife 76, moves said blank forwardly to the position E where the blank is registered against yieldable stop members 90 144, 144 that are fixed on shafts 145, 145 and project inwardly of the guide rails 86 and 89 so as to be normally positioned in the path of travel of the moving reopened carton blanks. The shafts 145, 145 are journaled in 95 bearing brackets 146, 146 that are bolted or otherwise suitably secured to the guide rails 86 and 89. Fixed on the shafts 145, 145 are arms 147, 147 to the free ends of which are connected springs 148, 148 that provide for 100 yielding movement of the stops 144, 144 out of the path of travel of the carton blank when it is pushed forwardly of said stops by the pusher 88. The springs 148 are connected, as by hooks or screw eyes 149, 149, with stationary parts of the machine, and said springs, 105 after the carton blank has passed the stops 144, 144, swing said stops into the full line positions thereof shown in Fig. 3 of the drawings.

110 The support for and motion of, the pusher 88, are preferably derived from the following instrumentalities. Fixed on the cam shaft 41 is a cam 150 provided with a groove 151 in which is engaged a roller 152. The roller 152 is carried by an arm 153 loosely mounted on the rock shaft 95. Pivotally connected with the arm 153 is one end of a connecting rod 154 the opposite end of which is 115 bent and pivotally connected with one arm 155 of a bell crank 156. The bell crank 156 is fixed on a stub shaft 157 that is journaled in a suitable bearing on the side frame 34 of the feeder. The other arm 158 of the bell crank 156 is pivotally connected with one extremity of a link 159 the opposite extremity of which is pivotally connected with a plate 160 that carries L-shaped arms comprising the pusher 88. On one side of the plate 160 is a lug 161 that carries on the end 120 125 130

thereof a crosshead 162 that slides in a horizontally extending groove 163 of a guide 164. The crosshead 162 is retained in the groove 163 by plates 165, 165 that engage over the crosshead and are bolted or otherwise suitably secured to the guide 164 adjacent the edges of the groove 163 therein. Extending outwardly from the guide 164 is a lug 166 that is secured to the forward leg of the bracket 72. The crosshead 162, through the connections therefor with the cam 150, causes the pusher 88 to move the opened carton from the position D thereof (Fig. 4) forwardly against the stops 144 that register the carton at the position E, the carton then being moved forwardly by the pusher into the position F where the carton is received by mechanism that squares the carton out and moves it into position to be transferred onto one of the moving forms 33, 33 of the package making machine. The pusher 88 after moving the carton into said squaring out mechanism is returned to the full line position shown in Figs. 3 and 4 of the drawings, and is ready to push the next reopened carton forwardly as above described.

Squaring out mechanism, Figs. 1, 2, 3, 4 and 12

The carton squaring out mechanism is preferably comprised by a pocketed receiver 167 through an open side of which the reopened and registered carton blanks are pushed into said receiver by the pusher 88. This receiver, which is open at the bottom to provide for removal of the cartons therefrom, is mounted on the front of the blank feeder above the package making machine and in the same vertical plane with the continuously moving carton forms or blocks 33, 33 thereof. Said receiver is provided with fingers 168, which, in one position of the receiver are opened to permit movement of the carton into the pocket thereof, the fingers 168 being thereafter closed to square out the carton in the pocket of the receiver. The receiver 167 is reciprocated above and parallel with the continuously moving forms or blocks 33, 33 of the package making machine, and the motion of said receiver is so timed relative to that of the forms or blocks 33, 33 that, in one cycle of operation of the receiver, it moves in one direction from the point of transfer of the carton into the receiver, to a point where the carton is delivered onto one of the continuously moving forms or blocks 33, 33, whereupon the receiver is moved in the opposite direction to the first named point where the next reopened carton is pushed into the receiver to be moved therewith and transferred onto the next carton form or block of the package making machine. These operations are carried out in a substantially continuous manner, and preferably through

the medium of the following instrumentalities.

Fixed on the cam shaft 41 is a cam 169 provided with a groove 170 in which is engaged a roller 171. The roller 171 is journaled on an arm 172 intermediate the ends thereof, said arm being loosely mounted on the rock shaft 95, (Fig. 12). The roller 171 and the arm 172 are associated and mounted in substantially the same manner as the arms 94, 123, 153 and the rollers 93, 122 and 152 carried thereby respectively and forming part of the driving connections for operating the knife 76 and the pusher 88. Pivotally connected with the free end of the arm 172 is one extremity of a connecting rod 173, the opposite extremity of which is pivotally connected with the free end of an arm 174 that is fixed on a rock shaft 175. This rock shaft 175 is journaled in suitable bearings on the bracket 72 and fixed on said rock shaft is an arm 176 to the free end of which is pivotally connected one extremity of a link 177. The opposite extremity of the link 177 is pivotally connected with a crosshead 178 that, through the connections therefor with the cam 169, is reciprocated in a horizontally extending groove 179 of a guide 180. The crosshead 178 is retained in the groove 179 by plates 181, 181 which engage over the crosshead and are bolted or otherwise pivotally secured to the guide 180 adjacent the edges of the grooves 179 therein.

The guide 180 is secured to or formed integrally with a saddle 181' (Fig. 2) that is bolted or fastened in any other desired manner on a tie member 182 that is connected with the upper ends of the brackets 72 and 72'. This tie member 182 is clearly shown in Fig. 2* of the drawings, and has adjustably mounted thereon brackets 183, 183 in which the upper ends of the blank recollapsing rollers 85, 85 are journaled. The lower ends of the rollers 85, 85 are journaled on plates 184 and 185 that are adjustably mounted on brackets 186 and 187 respectively, bolted or otherwise suitably fastened on the side frames 34 and 35 of the feeder. The bracket 186, as clearly shown in Fig. 2*, is provided with an extension 188 that supports and has secured thereto the rear end of the carton supporting plate 87.

Projecting forwardly from the crosshead 178 and preferably formed integrally therewith are upper and lower horizontally extending plates 189 and 190 respectively that are joined together by a web 191. The receiver 167 is bolted or otherwise suitably secured to the plate 190 on the under side thereof as clearly shown in Fig. 12 of the drawings, and said receiver is provided at opposite sides thereof with ears 192, 192 in which are journaled rock shafts 193, 193 that carry the swinging fingers 168, 168. The fingers 168, 168 are curved outwardly around

opposed sides of the receiver 167 and then inwardly so as to be moved back and forth across the open rear side of the receiver. The free ends of the fingers 168, 168 carry right angle brackets 194, 194 which, together with the inner sides of the receiver and right angle brackets 195, 195 secured in the corners thereof (Fig. 3), serve to square out the carton when it is pushed into the receiver and engaged by the fingers 168, 168.

At the point in the path of travel of the receiver where a carton is moved therein by the pusher 88, the fingers 168, 168 are opened by a mechanism that is preferably constructed as follows. Fixed on the cam shaft 41 is a cam 196 provided with a groove 197 in which is engaged a roller 198. This roller 198 is journaled on a fork 199 that straddles the cam shaft 41 and is connected with the lower end of a connecting rod 200. The upper end of the connecting rod 200 is pivotally connected with an arm 201 that is fixed on a rock shaft 202 journaled in suitable bearings on the side frame 34 of the feeder. Fixed on the rock shaft 202 is an arm 203 to the free end of which is pivotally connected one extremity of a link 204. The connection for the link 204 with the arm 203 is preferably comprised by a toggle one part 205 of which has a horizontal pivotal connection 206 with the free end of the arm 203. The other part 207 of said toggle is threaded on the rod 204 and has a vertical pivotal connection 208 with the toggle part 205. The end of the rod 204 opposite that comprised by the toggle 205, 207 is pivotally connected with one arm 209 of a horizontally arranged bell crank 210. The bell crank 210 is fixed on a vertical stub shaft 211 that is journaled in a suitable bearing carried by the side frame 34 of the feeder. The other arm 212 of the bell crank 210 is pivotally connected with one extremity of a link 213 the opposite extremity of which is pivotally connected with the free end of an arm 214 that is fixed on a vertical stub shaft 215 journaled in a suitable bearing carried by the side frame 35 of the feeder.

The link 213 extends transversely across the front of the feeder and through the connections operated by the cam 196 is moved rearwardly and forwardly of the feeder and continuously maintained substantially at right angles to the side frames of said feeder. As the blank receiver 167 moves to the full line position shown in Fig. 3 of the drawings, the link 213 is moved rearwardly of the feeder into engagement with the rollers 216, 216 that are journaled on the free ends of arms 217, 217 fixed on the rock shafts 193, 193. Rearward movement of the link 213 and engagement of the same with the rollers 216, 216 turns the shafts 193, 193 so that the fingers 168, 168 are opened to pro-

vide for movement of the carton into the pocket of the receiver 167.

After the carton has been pushed into the receiver, the link 213 through the connections therefor with the cam 196, moves forwardly of the receiver out of engagement with the rollers 216, 216. The fingers 168, 168 are then closed on the carton in the receiver, the closing movement of said fingers being effected by springs 218, 218 the opposite ends of which are secured to the arms 217, 217, and to arms 219, 219 that project from and are secured to opposite sides of the receiver 167.

*Flap spreading and carton stripping devices, 80
Figs. 1, 2, 4, and 7 to 12 inclusive*

The continuously moving carton receiver 167 is provided with flap spreading fingers 220, 220' and with a carton stripper 221. 85 These devices are so arranged and operated that when the receiver 167 with a squared out carton therein is moved adjacent the position G (Fig. 4) where the carton is transferred onto the one of the moving carton forms or blocks 33, 33, the fingers 220, 220' which have been moved downwardly in the carton, act to spread the bottom flaps thereof to ensure that the carton will be engaged over the moving form. The transfer of the 90 carton from the receiver 167 onto the moving form, is effected by the carton stripper 221 which engages the top of the carton and pushes the same out of the receiver through the open bottom thereof and onto the moving form. When the carton has been pushed onto the form by the stripper 221, the latter is moved upwardly through the receiver to an inoperative position, the flap spreading fingers 220, 220' in the meantime having 95 been retracted and also moved upwardly through the receiver which then returns to the full line position shown in Fig. 3 of the drawings to receive the next reopened carton that is forwarded by the pusher 88 to said 100 receiver.

The above described operations of the flap spreader are preferably obtained through the medium of the following instrumentalities. Fixed on the cam shaft 41 is a cam 222 115 in the groove 222^a of which is engaged a roller 222^b journaled on the free end of an arm 222^c that is fixed on the rock shaft 95. Fixed on the rock shaft 95 is an arm 222^d to the free end of which is pivotally connected the lower extremity of a connecting rod 223. The upper extremity of the rod 223 is pivotally connected with the free end of an arm 224 that is fixed on a shaft 225 journaled in suitable bearings on the upper ends 120 of the arms 226, 226 of a bracket 227 that is bolted or otherwise suitably secured to the plate 189 of the crosshead 178. Carried by, and preferably formed integrally with, the arms 224 is a segmental gear 228 that meshes 125

with a pinion 229 mounted between the bracket arms 226, 226 on a shaft 230 that is journaled in suitable bearings on said arms. Fixed on the shaft 230 between the bracket arms 226, 226 is a spur gear 231 that meshes 5 with a rack 232 secured on or formed integrally with a vertically reciprocating bar 233 that is guided in a suitable opening 234 extending vertically through the web 191 of the crosshead 178. Carried on the lower end of the bar 233, as by a pin or bolt 235, is a block 236 (Fig. 7) which is preferably of rectangular shape in cross section and provided with slots 237 and 238 in the opposed sides thereof respectively. The flap spreading fingers 220, 220' are pivoted in the upper ends of the slots 237, 238, on pins 239 and 240 respectively that extend at right angles to each other through the walls of the block 236. The block 236 is provided intermediate 20 the ends thereof, with a bore 241 in which is arranged to slide a plunger 242, there being a spring 243 interposed between the upper extremities of said plunger and the bore 241 respectively. The plunger 242 is provided with slots 244 and 244' cut therein at right angles to each other respectively and into which portions of the flap spreading fingers 220, 220' extend in both the operative and inoperative positions of said fingers.

The plunger 242 is provided with projections 245, 245 adapted to engage the top portions of the continuously moving carton forms or blocks 33, 33. When the bar 233 is moved downwardly, engagement of the plunger 242 with one of the continuously moving carton forms or holders is effected, downward movement of the plunger is prevented, and a shoulder 246 on said plunger, 25 through the downward movement of the bar 233, exerts a camming action on the fingers 220, 220' so that said fingers are moved outwardly through the slots 237 and 238 of the block 236, into engagement with the lower 30 end flaps of the carton 79 and thus spread said flaps prior to transfer of the carton onto the moving carton form or holder. When the plunger 242 is disengaged from the carton form, through upward movement of the bar 233, the spring 243 moves the plunger downwardly in the bore 241, a camming shoulder 247 on said plunger then engaging the upper ends of the fingers 220, 220' and thereby retracting the lower ends of said fingers into 35 the block 236 through the slots 237 and 238.

The stripper 221 that engages the top of the carton and pushes it out of the receiver 167 onto one of the moving carton forms or blocks 33, 33, is preferably operated through the 40 medium of the following instrumentalities. Fixed on the guide 180 for the crossheads 178, is a stationary cam block 248 provided in the front face thereof with a cam groove 249. Engaged in the cam groove 249 is a roller 250 (Figs. 1 and 2) that is journaled on the

lower end of an arm 251 fixed on a rock shaft 252. This rock shaft 252 is journaled in suitable bearings in the upper ends of the arms 253, 253 of a bracket 254 that is bolted or otherwise suitably fastened on the plate 189 of the crosshead 178. Fixed on the rock shaft 252 is a segmental gear 255 that meshes with a spur gear 256 keyed or otherwise rigidly secured on a shaft 257 journaled in suitable bearings on the bracket arms 253, 253. Fixed on the shaft 257 is a spur gear 256' that meshes with a rack 257' secured to or formed integrally with a bar 258 which is guided in the opening 234 of the web 191. Secured to the lower end of the bar 258, as by bolts or rivets 259, 259 is a plate 260 the lower end of which forms the stripper 221.

From the foregoing it will appear that after the receiver 167 moves forwardly of the package making machine a certain distance, the roller 250 travels upwardly in the cam groove 249, thus swinging the arm 251 so that the segmental gear 255 and the spur gear 256 are operated to move the bar 258 and the stripper 221 downwardly. In the downward movement of the stripper, it engages the top of the carton in the receiver 167. At the time the receiver 167 begins to move forward, the bar 233, through the connections therefor with the rock shaft 95, moves downwardly 50 in the carton, and the fingers 220, 220' are operated, through engagement of the plunger 242 with the moving carton form, to spread the lower end flaps of the carton. While the flap spreaders are holding the flaps open and the receiver is moving forwardly, the stripper 221 is moved by the described driving connections therefor with the reciprocating receiver 167, downwardly into engagement with the top of the carton. As the stripper 221 continues to move downwardly and while the flap spreading fingers are holding the lower end flaps of the cartons open, said stripper begins to move the carton out of the receiver 167 through the open bottom thereof and onto the moving carton form. At this time the flap spreaders are moved upwardly with the bar 233 and retracted in the holder 236. As soon as the stripper 221 has pushed the carton onto the moving carton form, the receiver 167 begins to move rearwardly of the package making machine, whereupon the stripper is moved upwardly to its inoperative position and is ready to act on the next carton that is pushed into the receiver at its cooperative position with the pusher 88. It will thus appear that the flap spreader and the stripper move successively in one direction through the receiver 167 during forward movement thereof relative to the package making machine, and that said flap spreader and the stripper move successively in the opposite direction through the receiver during movement thereof rearwardly of the package making machine.

The flap spreading fingers and the associated operating devices therefore, instead of being mounted on the receiver 167, may be mounted on the conveyor of the package making machine in which case each of the continuously moving carton forms or blocks 33, 33 of said conveyor is equipped with flap spreading devices and operating means therefor. A construction of this character is disclosed in Figs. 13 to 15 inclusive wherein each continuously moving carton form or block is provided in the upper part thereof with slots 261 and 262 that are cut in the top of the form at right angles to each other and intermediate the extremities of the sides of said form. Extending transversely through the slots 261 and 262 are pins 263 and 264 that are fitted in suitable openings through the walls of the carton form or block. Mounted on said pins are flap spreading fingers 265 and 266, the operative positions of which are indicated in full lines in Figs. 13 and 14 of the drawings. The flap spreading fingers 265 and 266 are provided with weighted cams 267 and 268 that tend to swing the fingers into inoperative positions within the slots 261 and 262. Journaled in suitable bearings in the upper and lower ends of the carton form or block, and movable vertically in said bearings, is a rock shaft 269 on the upper end of which is fixed an annular cup-shaped plate 270 which, when said rock shaft is moved upwardly, engages the cams 267 and 268 and swings the flap spreading fingers out of their receiving slots to the operative positions thereof above referred to where said fingers engage the end flaps of a carton and spread said flaps prior to delivery of the carton onto the moving carton form or block.

Fixed on the lower end of the rock shaft 269 is an arm 271 on the free end of which is carried a roller 272 that is engaged by a suitable cam (not shown) mounted on the machine adjacent the line of travel of the block 33 and at the position where the carton is transferred onto the moving carton form or block. When the roller 272 engages said cam, the shaft 269 is rocked and at the same time moved upwardly by a cam 273 which, during rotation of the rod 269, rides up on a pin 274 or the like that is carried by the carton form. Upward movement of the shaft 269 causes the plate 270 to engage the cams of the fingers 265 and 266, thereby swinging said fingers out of their receiving slots into engagement with the end flaps of the carton to spread said flaps as above described. When the carton has been transferred onto the moving carton form or block, and as the latter continues to move forwardly, the roller 272 strikes a second cam (not shown) fixed on the framework of the package making machine adjacent the line of travel of the conveyor. Engagement of the roller 272 with said second cam turns the rock shaft 269 in a direction opposite to that of its

first turning movement, thereby disengaging the high part of the cam 273 from the pin 274 so that the shaft 269 and the plate 270 move downwardly by gravity and the fingers 265 and 266 drop by similar action into their receiving grooves at the top of the carton form or block. It will, of course, be understood that the cams which engage the roller 272 are of sufficient height to accommodate raising and lowering movements of the arm 271 and the rock shaft 269 during their above described turning movements.

Instead of equipping the carton forms or blocks with mechanical flap spreading devices, pneumatic flap spreading means may be employed. In this case each of the continuously moving carton forms or blocks 33, 33 is preferably provided in the top thereof with angularly extending air ducts 275 and 276 (Fig. 16) through which air, delivered from any suitable source into the hollow carton form or block, is blown to spread the end flaps of the carton as it is being transferred onto the continuously moving form or block. The air is supplied to the interior of the carton form or block in a manner well understood in the art and needing no detailed explanation in so far as respects the present disclosure.

Operation

It is believed that the operation of the machine will be readily understood from the above description of the various instrumentalities comprising the same. A stack of collapsed carton blanks is placed on the chains 56, 56 of the stack feeder, said chains being operated as described to feed the blanks forwardly to the knife 76. The knife strikes the foremost carton blank and is then raised upwardly into the same. Thereafter the knife is moved forwardly and turned so that its edge draws the opened carton through the rollers 85, 85 which recollapse the carton and bend the side panels thereof in directions opposite to those in which said panels were bent when the carton was first collapsed. As the knife moves forwardly of the rollers 85, 85 it starts to move downwardly and at the limit of the forward movement of the knife it is drawn out of the carton, turned in the direction opposite to that of its first turning movement, and moved rearwardly to engage the next carton on the front of the stack 59. At the point where the first carton is left on the plate 87 by the knife, said carton is pushed by the pusher 88 into the pocket of the reciprocating receiver 167, the fingers 168, 168 at this time being rocked out of the way as the carton enters the receiver. Said fingers are then rocked in the opposite direction into engagement with the carton thereby squaring the same out in the receiver.

After the carton has been delivered into the receiver, said receiver, together with the flap spreader and the stripper, moves forwardly

in vertical alinement with and at the same rate of speed as one of the continuously moving forms or blocks 33, 33. At the time the receiver 167 starts forward, the flap spreader is driven downwardly through the carton to a point where the fingers 220, 220' are extended to spread the lower end flaps of the carton. While the flap spreading fingers are holding the flaps open, the stripper starts the carton out of the receiver through the open bottom thereof and onto the continuously moving carton form or block. As soon as the stripper has moved the carton downwardly so that the flaps are engaged over the form or block, the flap spreader is moved upwardly in the receiver toward the inoperative position of said flap spreader. When the stripper 221 has completed the movement of the carton onto the continuously moving carton form or block, the receiver 167 starts rearwardly and through the driving connections therefor with said stripper moves the latter upwardly to its inoperative position. In the meantime the flap spreader has been returned to its uppermost position by the connections therefor with the rock shaft 95, and when the receiver reaches its cooperative position relative to the pusher 88, all of the parts on said receiver are ready to act on the next carton forwarded into the receiver by said pusher. It will of course be understood that the above described operations are repeated and carried out in a substantially continuous manner and that the capacity of production of the apparatus is thus materially increased.

The invention, as before stated, may be embodied in single or tandem form with various types of package making machines that operate at various speeds and have any desired capacity of production. It is therefore to be expressly understood that while one embodiment of the invention has been herein illustrated and described with more or less detail, the invention is not limited to such embodiment or otherwise than by the terms of the appended claims.

What is claimed is:

1. In apparatus of the character described, a carton holder continuously moving in one plane only, a carton receiver arranged to move into cooperative relation with said carton holder, and means for positively moving the carton out of the receiver onto said continuously moving carton holder.

2. In apparatus of the character described, a carton form or block continuously moving in one plane only, a carton holding receiver having its movement synchronized with said form or block at a point of transfer, means for operating said receiver, and means for positively moving a carton out of the receiver onto the continuously moving carton form or block at said point.

3. In apparatus of the character described, a movable carton support, a carton holding

receiver arranged to move into cooperative relation with said carton support, and a stripper for moving a carton from the receiver onto the carton support during movement of said support and said receiver.

4. In apparatus of the character described, a movable carton support, a carton holding receiver arranged to move into cooperative relation with said carton support, means for transferring a carton from said receiver onto said carton support, and a flap spreader for spreading flaps on the carton prior to transfer of the latter onto said carton support and during movement of the carton support and the receiver.

5. In apparatus of the character described, a movable carton support, a carton holding receiver arranged to move into cooperative relation with said support, means for squaring out a carton on said receiver, and means for positively moving the squared out carton out of the receiver onto the movable carton support during movement of the latter and the receiver.

6. In apparatus of the character described, a receiver movable in opposite directions, a continuously moving carton support arranged to travel past the receiver, means for delivering a carton to said receiver, operating means for the receiver adapted to alternately move it into cooperative relation with said delivering means and the carton support, and means for positively moving the carton out of the receiver onto the movable carton support during movement of the latter and said receiver.

7. In apparatus of the character described, means for supporting a stack of collapsed cartons, means adapted to separate a carton from the stack, open the carton and move it away from the stack, a movable receiver to which the open carton is delivered, a continuously traveling carton support movable into cooperative relation with said receiver, and means for positively moving the carton relatively to the receiver to transfer said carton onto said carton support during movement of the latter and the receiver.

8. In an apparatus of the character described, means for supporting a stack of collapsed cartons, a carton holding receiver, means through which cartons are passed to recollapse the same, means adapted to separate a carton from the stack, open the carton, move it through said recollapsing means to a position where the carton is reopened and deliver it to said receiver, a continuously moving carton support, and means for positively moving the reopened carton out of the receiver onto the continuously moving carton support.

9. In an apparatus of the character described, means for supporting a stack of collapsed cartons, a pair of rollers through which cartons are passed to recollapse the

same, means adapted to separate a carton from the stack, open the carton, and move it through said rollers to a position where the carton is reopened, movable carton receiving and squaring out mechanism, means for delivering the reopened carton to said mechanism, a continuously moving carton supporting device, and means for transferring the opened and squared out carton from said mechanism onto said carton support while said device and mechanism are in motion.

10. In apparatus of the character described, an endless conveyor provided at intervals therealong with carton forms or the like, means for supporting a stock of collapsed cartons, a reciprocating carton receiver, means adapted to separate a carton from the stack, open the carton and move it to a position from which the carton is delivered to said receiver, and means for moving the carton relatively to the receiver to transfer said carton onto one of the forms of the conveyor.

11. In apparatus of the character described, a conveyor provided at intervals therealong with a plurality of carton forms or the like, means adapted to support a stock of collapsed cartons, a movable receiver, means for separating the cartons successively from the stack adapted to open the cartons, move the same, and position the cartons for delivery to said receiver, means for pushing the opened cartons to the receiver, and means for moving the cartons relatively to the receiver to transfer said cartons onto the forms of said conveyor.

12. In apparatus of the character described, means for supporting a stack of collapsed cartons, a rotatable knife movable rectilinearly in angularly related directions to separate a carton from the stack, open and move the carton away from the stack and repeat said operations on the successive blanks of the stack, a conveyor provided at intervals thereon with carton forms or the like, and means for moving the opened cartons successively into position on the successive forms of said conveyor.

13. In apparatus of the character described, means for supporting and feeding a stack of collapsed cartons, a reciprocating knife movable in a closed path, means for moving the knife in said closed path so that it engages the foremost collapsed carton, moves upwardly therein, then forwardly with a turning motion to separate the carton from the front of the stack, open said carton, and carry it forwardly to a position where the carton is reopened, a movable form or the like, and means for moving the carton from said position onto said form.

14. In apparatus of the character described, means for supporting and feeding a stack of collapsed cartons horizontally, a pair of normally fixed vertical rollers arranged

forwardly of said means and through which the cartons are drawn to a position where they are reopened, a knife reciprocating vertically and horizontally and adapted to engage the foremost carton of the stack, move upwardly in said carton, forwardly therewith through the rollers to said position, and then downwardly out of the cartons and rearwardly into engagement with the next carton on the front of the stack, an endless chain conveyor movable transversely of the path of movement of said stack, a plurality of forms secured at intervals along said conveyor, and means for moving the reopened cartons onto said movable forms.

15. In apparatus of the character described, means for supporting and feeding a stack of collapsed cartons, a rotatably mounted knife reciprocating vertically and horizontally and adapted to engage the foremost carton of the stack, move upwardly in said carton, forwardly therewith to a position where the carton is reopened, and then downwardly out of the carton and rearwardly into engagement with the next carton on the front of the stack, means for rotating the knife in one direction as it starts forwardly with the carton, means for thereafter rotating the knife in the opposite direction, a plurality of movable forms, and means for moving the reopened cartons onto said movable forms.

16. In apparatus of the character described, a knife mounted to rotate and travel in a closed path, mechanism for moving the knife in its closed path, and means independent of said mechanism and adapted to rotate the knife as it travels in said path.

17. In apparatus of the character described, a rotatably mounted knife arranged to travel in a closed path, mechanism for moving said knife in its closed path, and means independent of said mechanism and adapted to rotate the knife first in one direction and then in the opposite direction as it travels in said path.

18. In apparatus of the character described, a blank support, a device to which blanks are fed from said support, a movable knife for feeding said blanks, mechanism for moving said knife rectilinearly in angularly related directions along a closed path, and devices for rotating the knife as said knife travels in said path.

19. In apparatus of the character described, a device to be fed, means for feeding blanks thereto comprising a rectilinearly reciprocating cross-head and a knife arranged to reciprocate rectilinearly on said cross-head transversely of its path of travel, means for reciprocating said knife, and means for turning the knife during the reciprocating movement of the cross-head and the knife.

20. In apparatus of the character described, a device to be fed, means for feeding blanks thereto comprising a knife, a horizontal

zontally movable cross head on which the knife is arranged to rotate and travel vertically, means for reciprocating said cross head horizontally, means for reciprocating the knife vertically on the cross head, and means for rotating the knife during reciprocating movements of the cross head and said knife.

21. In apparatus of the character described, a device to be fed, means for feeding blanks thereto comprising a rotatably mounted knife, means for moving said knife rectilinearly in angularly related directions along a closed path, and means for rotating the knife first in one direction and then in the opposite direction during travel of the knife in said path.

22. In apparatus of the character described, a device to be fed, means for feeding blanks thereto comprising a rotatably mounted knife, mechanism for moving said knife rectilinearly in angularly related directions, cam-operated means for rotating said knife in one direction, and a spring for rotating the knife in the opposite direction.

23. In combination, a rectilinearly reciprocating crosshead, a knife support arranged on said crosshead for rectilinear reciprocating movement transversely of its path of travel, a knife cam-operated in one direction and spring-operated in the other direction and rotatably mounted on said knife support, means for reciprocating the crosshead, and means for reciprocating the knife support.

24. In combination, a rectilinearly reciprocating crosshead, a bar or the like arranged for rectilinear reciprocating movement on the crosshead transversely thereof, means for reciprocating the crosshead, means for reciprocating said bar, a knife holder rotatably mounted on the bar and having an arm provided at the end thereof with a roller, a knife carried on said knife holder, a cam for engaging said roller to turn the knife in one direction, and a spring for turning said knife in the opposite direction.

25. In combination, a knife support, means for moving said support rectilinearly in angularly related directions, a knife holder rotatably mounted on said support, said knife holder being cam-operated in one direction and spring-operated in the opposite direction, a knife pivoted on the knife holder on an axis extending substantially at right angles to the longitudinal axis of the knife, and means providing for yielding movement of the knife about its pivotal connection with said knife holder.

26. In combination, a knife support, a vertical trunnion thereon, means for moving said support in a closed path, a knife holder journaled on said trunnion and movable with the support in said path, a knife pivoted on said holder on an axis extending transversely of the trunnion, and means providing for yield-

ing movement of the knife about its pivotal connection with said holder.

27. In apparatus of the character described, means to be fed, means for feeding blanks thereto comprising a rotatably mounted knife, mechanism for moving said knife in a closed path, and blank recollapsing means in said path through which the knife with the blank thereon passes during its travel in said path, and means independent of said mechanism and adapted to rotate the knife in reverse directions at opposite sides of said blank recollapsing means respectively.

28. In apparatus of the character described, means to be fed, a movable knife for feeding blanks thereto, mechanism for moving said knife in a closed path, and a pair of blank recollapsing rollers normally immovable relative to each other and through which the knife with the blank thereon passes during travel of said knife in said path.

29. In apparatus of the character described, means for supporting a stack of carton blanks, a reciprocating pusher to which blanks are fed successively from said supporting means, a rotatably mounted knife for feeding said blanks, and independent mechanisms for rotating and moving said knife in a closed path respectively.

30. In apparatus of the character described, means for supporting a stack of carton blanks, means to which blanks are fed successively from said supporting means, a rotatably mounted knife for feeding said blanks and arranged to reciprocate rectilinearly in a plurality of angularly related directions, mechanism for reciprocating the knife rectilinearly in each of said directions, a pair of rollers through which the knife with a blank thereon passes, and means for rotating the knife in reverse directions rearwardly and forwardly of said rollers, respectively.

31. In combination, a carton receiver, mechanism for reciprocating the same horizontally, means for pushing cartons into said receiver, spaced horizontally movable fingers pivoted on the receiver for squaring out the carton therein, means for opening said fingers, and means for closing the same.

32. In combination, a reciprocating receiver open at the bottom and one side thereof, means for pushing a previously opened carton into the receiver through its open side, devices pivoted on the receiver for squaring out the carton therein, mechanism for opening the pivoted devices when the carton is moved into the receiver, means for thereafter closing said devices, and means traveling with and movable relatively to the receiver for pushing the squared out carton out of the receiver through the open bottom thereof.

33. In combination, a reciprocating carriage, a carton receiver secured thereon, means on said receiver for squaring out a car-

ton therein, an element arranged on the carriage to travel therewith and move into a carton in the receiver, flap spreaders carried by the element and adapted to spread the flaps of the carton, and mechanism for reciprocating said element during like motion of the carriage and said receiver.

34. In combination, a carton receiver and a flap spreader holder movable together as a unit and along paths extending transversely of each other, mechanism for reciprocating the receiver and said flap spreader holder together as a unit, and mechanism for reciprocating said flap spreader holder transversely of the path of movement of said receiver.

35. In combination, a carton receiver and a stripping device movable together as a unit and along paths extending transversely of each other, mechanism for reciprocating the receiver and said stripping device, together as a unit, and mechanism for reciprocating the stripping device transversely of the path of movement of said receiver.

36. In combination, a reciprocating carton receiver, flap spreading means arranged to be reciprocated relative to the receiver, a holder for said means traveling with the receiver and movable transversely of its path of travel, means for reciprocating the holder during like motion of the receiver, a device traveling with the receiver and movable transversely of the path of movement of the receiver for removing a carton therefrom, and mechanism for reciprocating said device during movement of the receiver and said holder.

37. In combination, a reciprocating carton receiver, an element traveling with and movable transversely of the path of movement of said receiver and provided with flap spreading means, a movable carton holder arranged to contact a part of said means to operate the same and spread the flaps of the carton on said receiver, and means traveling with the receiver and movable transversely of its path of movement for thereafter transferring the carton onto said carton holder.

38. In combination, a horizontally reciprocating carton receiver, a gear-operated member traveling therewith and movable up and down in the receiver, flap spreading means on said member, a movable carton holder adapted to engage a part of said means to operate the same and spread the flaps of a carton on the receiver, and a gear-operated member traveling with the receiver for thereafter transferring the carton from the receiver onto said carton holder.

39. In combination, a reciprocating carton receiver, mechanism for reciprocating the same, flap spreading means arranged for reciprocating movement on the receiver, means for reciprocating the flap spreading means as the receiver is reciprocated, a carton stripper arranged for reciprocating movement on the receiver, a stationary cam, and connec-

tions between said cam and the carton stripper for reciprocating the latter during like motion of the receiver and said flap spreading means.

40. In apparatus of the character described, mechanism for supporting and feeding a stack of collapsed cartons, a continuously traveling form having a path of movement extending transversely of the path of movement of said stack, a reciprocating knife for separating a collapsed carton from the stack and for opening the carton and moving it to a position adjacent the path of movement of the continuously traveling form, and means for transferring the carton from said position onto said form.

41. In apparatus of the character described, mechanism for supporting and feeding a stack of collapsed cartons in a substantially horizontal path, a continuously traveling form having a path of movement extending transversely of the path of movement of said stack, a pair of carton recollapsing rollers disposed between said mechanism and the form and normally immovable relative to each other, means for separating a collapsed carton from the stack and for opening said carton and forwarding it through said rollers to a position where the carton is reopened adjacent the path of movement of the continuously traveling form, and means for transferring the reopened carton from said position onto said continuously traveling form.

42. In apparatus of the character described, a continuously moving carton form, carton carrying means movable in one direction to receive the carton and in the opposite direction to bring it into alinement with said form, and means traveling in said directions with the carton carrying means and adapted to move transversely of its path of travel and transfer the carton from said carrying means onto the form when said carton is brought into alinement therewith.

43. In apparatus of the character described, a continuously moving carton form, carton squaring means movable in one direction to receive the carton and in the opposite direction to bring it into alinement with said form, a device traveling in said directions with the carton squaring means and adapted to move transversely of its path of travel and transfer the carton from said squaring means onto said form when said carton is brought into alinement therewith, and mechanism for reciprocating the carton squaring means and said device.

44. In apparatus of the character described, a movable carton form, carton squaring means movable in opposite directions into and out of cooperative relation with said form, and a reciprocating stripper arranged to travel in said directions with the carton squaring means and adapted to move trans-

versely of its path of travel and transfer the carton from said squaring means onto the form when the squaring means is moved into cooperative relation with said form.

45. In apparatus of the character described, a movable carton form, carton carrying means movable in opposite directions into and out of cooperative relation with said form, a pair of devices arranged to travel in said directions with the carton carrying means and adapted to move transversely of its path of travel and successively spread the flaps of the carton and transfer it onto the form when the carrying means is moved into cooperative relation therewith, and mechanism for reciprocating said carrying means and said devices.

46. In apparatus of the character described, a movable form, a carton receiver movable in opposite directions into and out of cooperative relation with said movable form, oscillating devices on the receiver for squaring the carton thereon, and reciprocating means traveling in said directions with the receiver and said devices and adapted to transfer the carton onto said form when the receiver is moved into cooperative relation therewith.

47. In apparatus of the character described, a movable form, carton engaging mechanism movable as a unit in opposite directions relative to the form and comprising carton squaring means and means for successively spreading flaps of the carton and moving it from said carton squaring means onto the movable form, means for pushing the carton onto said squaring means, and means for reciprocating said carton engaging mechanism as a unit to alternately bring the carton squaring means into cooperative relation with said pushing means and said movable form.

48. In apparatus of the character described, mechanism for supporting and feeding a stack of collapsed cartons, reciprocating means adapted to separate a carton from the stack, open the carton, and carry it to a position removed from the stack, means movable in opposite directions along a path extending transversely of the path of movement of said reciprocating means and adapted to receive the open carton from said position, carton transferring means associated with the carton receiving means and movable therewith in opposite directions along its path of movement, a carton form movable into alignment with the carton receiving means at a point adjacent its path of movement, and means for operating the carton transferring means at said point whereby said carton transferring means moves the carton from the receiving means onto said form.

49. In apparatus of the character described, mechanism for supporting and feeding a stack of collapsed cartons, a contin-

uously driven endless chain provided at intervals therealong with forms and having a path of movement extending transversely of the path of movement of said stack, a reciprocating knife movable in a closed path between said mechanism and said chain and adapted to separate a collapsed carton from the stack, open and move the carton toward the travelling forms and repeat said operations on the successive blanks of the stack, and means independent of said knife for moving the open cartons successively into position on the successive forms of said endless chain.

50. In apparatus of the character described, means for supporting and feeding a stack of collapsed cartons, a plurality of continuously moving forms arranged to travel in a path extending transversely of the path of travel of said stack, carton recollapsing means interposed between said first named means and said forms and through which the cartons are drawn and reopened at a position adjacent the path of travel of the movable forms, a knife reciprocating vertically and horizontally and adapted to separate, open and forward the collapsed cartons successively through said carton recollapsing means to said position, and means for moving the reopened cartons successively onto the successive continuously moving forms.

51. In apparatus of the character described, a blank support, a device to which blanks are fed from said support, means for feeding said blanks from the support to said device and comprising a knife mounted to rotate and travel rectilinearly in a plurality of angularly related directions, mechanism for moving said knife rectilinearly in each of said directions, and devices for rotating the knife.

52. In apparatus of the character described, a knife arranged to rotate and travel rectilinearly in a plurality of angularly related directions, means for moving the knife rectilinearly in each of said directions, and means for rotating the knife during travel of said knife.

53. In apparatus of the character described, a knife arranged to rotate and travel rectilinearly in a plurality of angularly related directions, means for moving the knife rectilinearly in each of said directions, and means for rotating the knife first in one direction and then in the opposite direction during travel of the knife.

54. In apparatus of the character described, a rotatably mounted knife, mechanism for moving said knife in a closed path, cam operated means for rotating said knife in one direction as it travels in said path, and a spring for rotating the knife in the opposite direction as it travels in said path.

55. Blank separating and forwarding means arranged to travel in a closed path and comprising a knife adapted to reciprocate rectilinearly in a plurality of angularly

related directions and to rotate while traveling in said path.

56. Blank separating and forwarding means comprising a knife arranged to reciprocate rectilinearly in a plurality of angularly related directions and rotate first in one direction and then in the opposite direction.

57. In apparatus of the character described, a continuously moving carton form or block, a reciprocating knife for separating a collapsed carton from a stack and adapted to open said carton, and means for moving the opened carton into position on said continuously moving form or block.

58. In apparatus of the character described, a continuously moving carton form or block, a reciprocating knife for separating a collapsed carton from a stack and adapted to open said carton, and a reciprocating receiver or pocket adapted to move the opened carton into position on said continuously moving form or block.

59. In apparatus of the character described, a movable carton support, a carton holding receiver arranged to move into co-operative relation with said carton support, and a reciprocating stripper mounted on the receiver and movable transversely of its path of travel to push a carton from said receiver onto the carton support.

In testimony whereof I have signed this specification.

GEORGE H. BENT.
